UNITED STATES PATENT OFFICE.

CHARLES H. MORRILL, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

ART OF MAKING GAITERS.

Application filed September 26, 1921. Serial No. 503,312.

This invention relates to the art of manufacturing gaiters from material containing a vulcanizable substance.

Hitherto the manufacture of such gaiters has been carried out by wrapping about a form a one-piece lining the edges of which are fastened together permanently, building the outer of the gaiter upon the lining by laying upon the lining various pieces and 10 rolling them into contact with the lining and with each other, making the buttonholes, fastening the buttons and the strap in place, then vulcanizing the gaiter and finally slitting the lining and removing the gaiter from 15 the form. This procedure is in many respects unduly laborious, as for example the pressing of the parts one by one as the outer is built up on the lining. It is very desirable that this pressure be sufficient to expel 20 all entrapped air and bring the parts into intimate contact, since otherwise blisters will be formed during the subsequent vulcanization; but it is difficult to secure satisfactory contact by using a hand roller on 25 the parts while they are upon the form, which has been the usual practice. Moreover, so far as I am aware, the old method has been used only for the manufacture of rough, heavy gaiters in which smoothness of 30 fit and neatness of appearance were not essential. The general object of the present invention is to produce an improved gaiter of the vulcanized type.

According to the present invention both 35 the outer and the lining are cut to fit the vulcanizing form but are not placed upon that form until they have been pressed together, preferably by a rolling machine, so as to bring them into intimate contact and 40 to expel all entrapped air. Preferably the partly-formed gaiter which may consist of the outer, the lining, and various stay pieces, after having been subjected to pressure, is 45 temporarily secured upon the form and subjected to vulcanization. It may then be removed from the form (no cutting of the lining being necessary), and completed, that is, the button-holes made, the buttons fastened in place and the strap attached. It 50 will be understood, however, that the particular order in which the steps have been mentioned above is not essential except that the outer and lining are pressed together

prior to securing them temporarily upon the form preparatory to vulcanization. 55

Referring to the accompanying drawings,—

Fig. 1 is an elevation of the three pieces of the outer;

Fig. 2 is an elevation of the same pieces after they have been stitched together wrong side out to form the outer; 60

Fig. 3 is a perspective showing the pressing of one of the seams of the outer;

Fig. 4 is a perspective of the outer after 65 the seams have been pressed and coated with cement, one of the stays and part of the piping having been laid in place;

Fig. 5 is an elevation of the parts of the lining; 70

Fig. 6 shows one piece of the lining in process of being applied to the outer;

Fig. 7 shows the other two pieces in the process of being applied;

Fig. 8 shows the partly completed gaiter 75 temporarily fastened upon a vulcanizing form, and

Fig. 9 shows a complete gaiter.

In the manufacture of the gaiter, the outer is made in three sections, a main section 80 11, a button fly section 13, and a buttonhole fly section 15, these sections being cut to pattern so that when they are fastened together they will fit about a vulcanizing form which will presently be described. These 85 sections of the outer are fastened together wrong side out by any suitable means, for example by stitched seams as indicated in Fig. 2. The seams are then pressed, for example by means of a roller 17 as indicated in Fig. 3. There is next placed around the entire edge of the outer a strip or strips of piping 20. The outer is preferably made of rubberized jersey cloth and the piping, stays and lining of some sort of friction fabric, 90 all of these parts being tacky on one or both sides so that they adhere when placed in contact. After the piping has been laid, the buttonhole stay 19 and the button stay 21 are laid along the margins of the sections 15 95 and 13. A stripe of cement is now placed over the two seams which connect the three parts of the outer, said stripes being indicated at 23, Fig. 4. The middle section 25 of the lining, which is made of rubberized 100 fabric, is now laid in place in the manner 105

indicated in Fig. 6 with its margins against the stripes of cement 23. Stripes of cement 27 are placed along the margins of the main section 25 of the lining and thereafter the 5 buttonhole section 29 of the lining and the button section 31 are laid in place in the manner indicated in Fig. 7.

In order to bring all the parts of the gaiter which have been thus far assembled into 10 intimate contact so as to expel any entrapped air and to cause the parts to adhere firmly to one another, the partly assembled gaiter is subjected to a pressing operation, preferably by means of a rolling machine. At 15 any rate, the parts are forced into intimate contact before the next step in the procedure, which is to wrap the partly made gaiter about a form 33 and secure it temporarily in place in some suitable manner, as for example by tacks 35, this form serving to hold 20 the gaiter in the desired shape during vulcanization. After the vulcanization has been completed, the gaiter is removed from the form, the buttonholes 37 are made, the 25 buttons 39 fastened in place, and the usual strap 41 with its buckle is attached.

By pressing the rubberized parts of the gaiter together before placing them upon the form, a much more intimate contact of 30 the parts is secured and a much neater appearance secured in the finished gaiter. This neat appearance is also due to the cutting of the parts of the outer to pattern so that when they are sewed together, the outer thus 35 made will fit snugly about the form, as well as to the fact that the buttonholes are made and the buttons fastened in place after vulcanization.

Although the invention has been described 40 in connection with a certain order of steps, and in connection with the employment of particular stays and piping, it should be understood that the invention is not limited in its broader aspects to the particular parts employed or to the particular order of the 45 steps.

Having thus described my invention, what I claim as new and desire to secure by Letters Patent of the United States is:

50 1. The method of making a gaiter from materials containing a vulcanizable substance which comprises providing three outer sections comprising a main section the front and rear edges of which are curved at 55 about the level of the ankle to provide for the curve of the instep and that of the back of the heel of the wearer, a rear section having an edge curved to correspond to the curve of the rear edge of the main section 60 and a front section having an edge curved to correspond to the curve of the front edge of the main section, sewing the sections together wrong side out to form an outer, pressing the seams, applying a lining to the 65 outer thus made and completing the manu-

facture of the gaiter including wrapping the composite piece thus made about a form with its free ends overlapped, fastening the overlapped ends to the form, subjecting the composite piece to vulcanization, removing 70 the fastenings and unwrapping it from the form.

2. The method of making a gaiter from materials containing a vulcanizable substance which comprises providing outer and lining parts shaped to fit upon a form, fastening the parts together and pressing them after they have been fastened in order to bring the parts of the lining into intimate contact with those of the upper, and thereafter completing the manufacture of the gaiter, including wrapping the outer and lining thus pressed together, about a form in such manner that the free ends overlap 80 at the side of the form, subjecting them to 85 vulcanization, unwrapping them from the form, making the buttonholes, and fastening the buttons in place.

3. The method of making a gaiter from materials containing a vulcanizable substance which comprises cutting the outer and lining parts from sheet material, laying the lining on the outer and pressing the two together, wrapping the gaiter thus partly made about a form adapted to impart to it 95 the desired shape, the wrapping being done in such manner that the free ends overlap at the side of the form, subjecting it to vulcanization while thus held on the form, unwrapping the partly made gaiter from about 100 the form, and completing its manufacture.

4. The method of making a gaiter from materials containing a vulcanizable substance which comprises cutting the outer and lining parts from sheet material, laying 105 the lining on the outer and pressing the two together, thereafter wrapping the partly made gaiter about a form in such manner that the free ends overlap at the side of the form, subjecting it to vulcanization, unwrapping it from the form, forming the buttonholes, fastening the buttons in place, and fastening the strap.

5. The method of making a gaiter from materials containing a vulcanizable substance which comprises providing three outer sections; a main section, a button fly section and a buttonhole fly section; fastening the sections together to form an outer in such manner as to leave one edge of each 115 of the two last-named sections free, applying a lining to the outer, pressing the lining and the outer together, and thereafter completing the manufacture of the gaiter, including temporarily wrapping the partly 120 made gaiter about and fastening it to a form, subjecting it to vulcanization, and thereafter unfastening and unwrapping it.

6. The method of making a gaiter from materials containing a vulcanizable sub-

- stance which comprises providing three outer sections, a main section, a button fly section and a buttonhole fly section, fastening the sections together to form an outer in such manner as to leave one edge of each of the two last-named sections free, applying a lining to the outer, pressing the lining and the outer together, and thereafter completing the manufacture of the gaiter, including wrapping the partly made gaiter about a form, subjecting it to vulcanization, unwrapping it from the form, and making the buttonholes in and fastening the buttons to the vulcanized material.
7. The method of making a gaiter from materials containing a vulcanizable substance which comprises providing three outer sections, a main section, a button fly section, and a buttonhole fly section, fastening the sections together in such manner as to leave one edge each of the two last-named sections free, providing a three-piece lining, applying the pieces one at a time to the outer, pressing the outer and lining together to bring them into intimate contact and completing the manufacture of the gaiter, including securing the outer and lining, fastened together as described, temporarily upon a form and subjecting them to vulcanization.
8. The method of making a gaiter from material containing a vulcanizable substance which comprises providing three outer sections, a main section, a button fly section, and a buttonhole section, fastening these sections together to form an outer in such manner as to leave one edge of each of the two last-named sections free, providing three similar lining sections, superposing the lining sections upon the outer, subjecting the lining and outer to a rolling operation to press them into intimate contact, and thereafter completing the manufacture of the gaiter, including temporarily securing the partly made gaiter upon a form and subjecting it to vulcanization.
9. The method of making a gaiter from materials containing a vulcanizable substance which comprises providing three outer sections, a main section, a button-fly section and a buttonhole section, fastening these sections together to form an outer in such manner as to leave one edge of each of the two last-named sections free, providing three similar lining sections, superposing the lining sections upon the outer, subjecting the lining and outer to a rolling operation to press them into intimate contact, and thereafter completing the manufacure of the gaiter including temporarily securing the partly made gaiter upon a form, subjecting it to vulcanization, removing it from the form and making the buttonholes in and fastening the buttons to the vulcanized material.
10. The method of making a gaiter from materials containing a vulcanizable substance which comprises providing three outer sections, a main section the front and rear edges of which are curved at about the level of the ankle to provide for the curve of the instep and that of the back of the heel of the wearer, a rear section having a curved edge to correspond to the curve of the rear edge of the main section, and a front section having a curved edge to correspond to the curve of the front edge of the main section, fastening the curved edges of the sections together to form an outer, applying a lining to the outer thus made, and completing the manufacture of the gaiter, including temporarily securing the outer and lining upon a form, and subjecting it to vulcanization.
11. The method of making a gaiter from material containing a vulcanizable substance which comprises providing three outer sections, a main section the front and rear edges of which are curved at about the level of the ankle to provide for the curve of the instep and that of the back of the heel of the wearer, a rear section having a curved edge to correspond to the curve of the rear edge of the main section, and a front section having a curved edge to correspond to the curve of the front edge of the main section, sewing the curved edges of the sections together to form an outer, pressing the seams, applying a lining to the outer thus made, and completing the manufacture of the gaiter, including temporarily securing the outer and lining upon a form and subjecting it to vulcanization.
12. The method of making a gaiter from material containing a vulcanizable substance which comprises providing three outer sections, a main section, the front and rear edges of which are curved at about the level of the ankle to provide for the curve of the instep and that of the back of the heel of the wearer, a rear section having a curved edge to correspond to the curve of the rear edge of the main section, and a front section having a curved edge to correspond to the curve of the front edge of the main section, fastening the curved edges of the sections together to form an outer, applying a lining to the outer thus made and completing the manufacture of the gaiter, including temporarily securing the outer and lining upon a form, subjecting it to vulcanization, removing it from the form, and making the buttonholes in and fastening the buttons to the vulcanized material.
13. The method of making a gaiter from materials containing a vulcanizable substance which comprises providing three outer sections, including a main section, a button fly section, and a buttonhole fly section, sewing the sections together to form an outer in such manner as to leave one edge each of the two

last-named sections free, pressing the seams, laying piping around the edge of the outer, laying stays on the button fly and the button-hole fly, laying a lining, subjecting the gaiter 5 thus partly made to a pressing operation, securing the partly made gaiter temporarily upon a form, subjecting it to vulcanization, removing it from the form, making the buttonholes, fastening the buttons in place, and 10 attaching the strap.

14. The method of making a gaiter which consists in cutting from suitable rubberized cloth three sections of such shape that when sewed together at their corresponding edges 15 they will constitute a covering adapted to fit a vulcanizing form, sewing the three parts together, and thereafter completing the manufacture of the gaiter including wrapping the covering about the form, the wrapping 20 being done in such manner that the free ends overlap at the side of the form, sub-

jecting it to vulcanization, unwrapping the covering from the form, and fastening the buttons to and forming buttonholes in the vulcanized article.

25

15. The method of making a gaiter from materials containing a vulcanizable substance which comprises providing outer parts and lining parts each of a plurality of pieces, sewing the outer parts together to form the outer, superposing the lining parts upon the outer parts, pressing the lining parts and the outer into intimate contact, wrapping the composite part thus formed about a form in such manner that the free ends overlap at 35 the side of the form and subjecting it to vulcanization, unwrapping it from the form, making the buttonholes and fastening the buttons in place.

30

16. In testimony whereof I have signed my 40 name to this specification.

CHARLES H. MORRILL.
